ERNEST C. WHITING, OF BRIGHTON, MASSACHUSETTS

COIN CONTROLLED APPARATUS

Application filed October 8, 1929. Serial No. 398,169.

This invention relates to improvements in coin controlled apparatus such as machines for dispensing commodities.

The present invention is directed more particularly to the mechanism for receiving the coin or coins and to permit the actuation of the dispensing mechanism by the same or otherwise to return the deposited or inserted coin or coins to the operator of the machine. My copending application Serial No. 370,482, filed June 13, 1929, discloses a vending machine which is especially adapted to the sale of articles such as periodicals, i. e., magazines or newspapers; this vending machine being provided with a swinging coin receptacle which retains a deposited coin in such a position that its edge may be engaged by an actuator to cause the movement of the receptacle to operate the dispensing mechanism.

The present invention affords a simplified machine of this general character which is provided with means permitting the retention of the deposited coins when an article is dispensed in exchange or the same and otherwise to return the coins. For the last-named purpose the machine is provided with means to support the return coins in an accessible position so that they may be readily removed without necessitating the use of a receptacle which might collect moisture when exposed out of doors. The mechanism provided by the present invention may be formed of a comparatively few sheet metal elements and includes a readily actuated trip means which permits the release of the coin or coins from the swinging coin receiving receptacle when an article is dispensed, and automatic means taking advantage of the inertia of a portion of the coin receptacle upon its return movement to release the coins to the return chute when an article has not been dispensed. The mechanism that may be readily adjustable to be actuated by a selected number or denomination of coins so that the same machine may be readily adapted, for example, to the sale of Sunday and daily papers which ordinarily have different prices, and if desired may be arranged to respond to the introduction of a single

coin or a plurality of coins collectively equaling such single coin in monetary value. A detector is also associated with the coin inlet passage to divert washers or the like, thus preventing the use of such articles as substitutes for coins.

In general this machine provides mechanism of this character which is formed of inexpensive sheet metal elements, which are arranged so that danger of breakage or wear is minimized and so that repairs may be readily made, when and if necessary.

In the accompanying drawings, which illustrate one concrete exemplification of the invention;

Fig. 1 is a front elevational view of a vending machine in which my invention is incorporated, a portion of the front cover being broken away;

Fig. 2 is an elevational detail of a portion of the dispensing mechanism and the swinging coin receptacle just as the coins are leaving the latter as a result of the operation of the trip mechanism;

Fig. 3 is a section on line 3—3 of Fig. 1; 75

Fig. 4 is a front elevational view of a portion of the coin control mechanism, part of the actuator being indicated in dot and dash lines;

Fig. 5 is a similar view, showing the position of parts of the mechanism when the coin receptacle is being swung due to the movement of the actuator;

swung by the secondary finger of the actuator; and

Fig. 14 is a diagrammatic side elevation of the coin receptacle illustrating the operation of the stop means.

A machine of the type illustrated in the accompanying drawings may comprise a box-like container 1 formed of sheet metal or the like and provided with a downwardly slideable cover 3 mounted in guideways 6 at the front of the box. The cover 3 is normally locked in the position shown in Figs. 1 and 3, and is arranged to provide an opening or slot 11 at the bottom of the front of the box through which articles such as newspapers may be delivered. An operating handle 13 is disposed at one side of the box and is secured to a rotatable shaft 14, Fig. 2, that is pivotally mounted on a frame member 17. The latter is secured by pocket-like clips 16 to the walls of the box-like container 1 so that it may be readily lifted out of its normal position in relation to the same. A coin receiving slot 16^a preferably is disposed above the operating handle, while a coin return passage terminates in an opening 19 below handle 13.

Referring first to Figs. 1 and 3, it is evident that a plurality of inclined article supporting members 20 may be disposed within the box 1 with their rear ends received in U-shaped socket elements 21 at the back of the box 1. The front ends of the supporting members 20 are secured to a transverse portion of the frame 17. Ejector elements 31 engage the foremost article upon supports 20 to prevent the article from moving off the supports. Elements 31 have rearwardly curved lips which are adapted to engage the rear marginal portion of the foremost article when they are swung about their pivotal supports 35. When this movement takes place the opposite wing portions of the ejector elements are moved out of their article retaining positions so that the foremost article is separated from the remainder of the group, the curved lip portions of the ejectors acting as temporary stops for the succeeding article. As soon as the parts are returned to the normal positions, the flat wing portions of the ejector elements again rise into engagement with the succeeding article which now has become the foremost article of the group. A link 50 connected by crank arms 51 to the axle elements 35 of the ejector elements is effective in swinging the latter about their axes, Fig. 2.

A swinging guard or apron 53 may be pivotally mounted in the delivery passage between the member 17 and the front of the container, being provided with a suitable spring 53^a which normally holds the apron across the delivery passage while the movement of the ejector elements, as shown in Fig. 2, is effective in moving the apron downward

to permit the movement of the article to the slot 11.

The mechanism which has just been described is of the general character which has been more completely described and disclosed in my above-identified copending application and affords an example of dispensing or delivering mechanism with which my coin receiving means, which more particularly forms the subject matter of the present invention, may be conveniently combined.

In accordance with the present invention, a coin receiving passage 70 is aligned with slot 16^a; the wall of this passage is provided with an opening 70^a at one side, which permits the removal of foreign objects that may be forced through slot 16^a. A depending plate 71 forms the lower portion of one side of the coin passage, being yieldably held in place by a spring 71^a. The rear of the passage has an opening which is aligned with the swinging coin receptacle that presently will be described. The bottom of the passage is provided by a narrow inclined plate 75 (Fig. 10) which is secured to the swinging actuator 64 that is mounted on shaft 14 and moves between the coin inlet passage and the swinging coin receptacle.

In order to prevent the operation of the machine by annular elements such as washers, a detector element is associated with the coin inlet passage. This element 170 is mounted upon a substantially horizontal axis 171 so that its plane of movement is substantially in the direction of coin movement approaching the inclined plate 75. A spring or weight tends to hold the member 170 in the position shown in Fig. 8 so that its inner end is yieldably held across the inlet passage above plate 75. It is evident that a coin or the like follows a substantially vertical path, thus gaining considerable momentum as it passes through the first part of the coin passage; when the coin engages the plate 75, it is diverted to a path which has a gradual inclination, i. e., a direction much nearer to the horizontal. The member 170 is located substantially at the juncture of these paths and is so arranged that it readily will swing when engaged by an edge of a vertically moving element, such as a coin or washer. In the case of the former, the movement in the gradually inclined direction, determined by the plate 75, may be continued without opposition from the detector, but in the case of a washer or the like the detector will engage the wall of its intermediate opening and will tend to prevent movement of such an article in the gradually inclined direction, i. e., in a direction intersecting the plane of detector movement at a substantial angle.

When the actuator is swung, the member 75 will however be moved away from the bottom of the coin passage, and the washer may move downwardly, the detector readily permitting

the movement in this direction. Thus, the washer may drop into the machine and be retained, without causing the machine to deliver an article.

5 Actuator 64 preferably is operatively connected to the shaft 14 so that it swings in response to the turning of handle 13. The coin receptacle includes a bottom plate or supporting member 60 having vertical flanges 10 60^a and 60^b which are pivotally mounted upon the shaft 14 so that the main plate may rotate about the same. A pivot element 117 on the front flange 60^a of the plate 60 is received in a slot 118 at the end of the link 50 15 (Fig. 2), so that movement of the plate actuates the link to operate ejector elements 31 to cause an article to be separated from the group supported by members 20 and to pass into the delivery passage. The front portion 20 of plate 60 is provided with a downwardly and rearwardly inclined coin supporting edge 100, and has a vertically disposed extension 101 at the rear of this edge, which supports an inclined shaft or pivot 25 element 80 that may be substantially parallel to the edge 100.

The coin receptacle comprises the upper or retaining portion 85 pivotally engaging the member 80 and comprising depending parallel walls 102 spaced to form the sides of the coin receptacle, (Fig. 7) the bottom of 30 which is provided by the edge 100. The front of shaft 80 is arranged so that the member 85 may readily be slid into engagement with the same or be removed therefrom. One of the parallel side walls 102 of retainer 85 is provided with an outstanding weighted extension 103 (Fig. 4) which tends yieldably to urge the retainer to a position out of alignment with the plane of plate 60. This tendency is normally opposed by a locking or 35 abutment element 130 (Fig. 3) which swings about a pivot 131 upon the plate 60, these parts being arranged so that the locking element swings in a path which is in juxtaposed parallelism to the plane of the plate. The locking element is thus arranged so that the coin receiving slot S (Fig. 7) between the 40 walls 102 of the receptacle is aligned with plate 60 so as normally to hold a coin in engagement with the inclined edge 100 as the receptacle is swung, due to the engagement of actuator finger 151 with a projecting portion 45 of the coin.

One side wall 102 of the coin receptacle is provided with a hole or holes 95 adapted to receive a stop member for limiting the movement of coins lengthwise of the receptacle. 50 Preferably, a plurality of holes 95 are provided, such holes being so spaced that by arranging the stop in a properly chosen hole, the capacity of the receptacle may be adjusted to permit actuation of the dispensing means in response to the introduction of a

selected member and/or denomination of coins.

Preferably the stop consists of a finger 91 (Fig. 7) forming one end of a spring clip which may consist of a length of resilient wire coiled at 92 and having the arms 92^a and 92^b. This clip is straddled over the upper edge of the coin receptacle, and the stop pin 91 is held in proper position in the selected hole 95 by the resiliency of the clip. This stop pin 91 determines the number of coins of a given denomination which may be placed in the receptacle and insures the positioning of such a coin or coins so that a portion of the last coin introduced shall be exposed beyond the end of the receptacle for engagement by the actuator finger 151. Thus as indicated in Fig. 14, two five-cent pieces *a* and *a'* have been placed in the receptacle, the first coin *a* resting against stop 91 while a portion *P* of the coin *a'* projects beyond the forward edges of the walls 102 and lies in the path of movement of actuator finger 151.

Moreover by arranging the holes 95 at the proper distance above the bottom of the receptacle the stop pin 91 selectively retains certain coins, for example five-cent pieces while permitting coins of smaller dimension, for example dimes to pass beneath and continue along the receptacle.

To permit the mechanism to act in response to the insertion of a single coin of relatively large denomination for example a dime, equalling in monetary value a row of coins of smaller dimension, for example the five-cent pieces *a* and *a'*, the actuator may be provided with a secondary finger or fingers, for instance the finger 151^a, secured to the shaft 14 so as to swing when the latter is turned, in the same way as finger 151. The walls 102 of the coin receptacle are provided with opposed slots 200 (Fig. 14) for the accommodation of the secondary finger 151^a and preferably the upper edge 100 of plate 60 has a notch in which the shank of the finger 151^a normally seats with its upper edge flush with the edge 100 so as to avoid interference with the movement of coins in the receptacle. Cooperating with the finger 151^a is a suitable stop, for example the vertical edge of part 101, or if preferred a pin similar to the pin 91 passing through a suitable opening in the side wall of the receptacle, such stop engaging a coin and stopping the latter with a portion of the coin exposed at the slot 200 and in the path of the secondary finger 151^a.

To permit a coin, for example a dime, to be used for actuating the machine while preventing its operation by a cent, the stop 91 may be arranged so as to permit a dime to pass beneath it while preventing the passage of a cent, the stop pin being at such a distance from the receiving end of the coin receptacle that if a row of cents be placed in

the receptacle, the last cent to be introduced will lie, either so far within the receptacle as not to engage finger 151, or so far out of the receptacle that it will not be engaged by the finger 151 to swing the receptacle to dispensing position. As thus arranged the mechanism will respond either to the introduction of two five-cent pieces which cooperate with the actuator finger 151 to initiate operation of the dispensing devices, or to the introduction of a dime which cooperates with the secondary finger 151^a in the same way, while the machine will not operate in response to the introduction of a cent or a plurality of cents into the receptacle.

Obviously any suitable arrangement of stops and actuator arms may be employed for permitting operation of the machine by coins of different dimensions and in different combinations.

The actuator 64 is mounted upon the shaft 14 so that it swings in response to a corresponding movement of the exterior handle 13. A spring 160 normally tends to return the actuator and connecting parts to their inoperative positions. A flange 61 upon the lower part of the actuator normally engages the plate 60, thus being adapted to determine the inoperative position of the actuator and also being effective in returning the coin receptacle to its inoperative position upon the return movement of the actuator due to the tension of spring 160. The upper edge of lug 61 engages the lower portion of frame member 17, thus acting as a stop to limit the swinging movement of the actuator 64.

When the stop 91 is properly positioned and the proper number of coins inserted, the last coin will project beyond the end of member 85 into the path of the finger 151 of the actuator 64, this position of the parts being illustrated in Fig. 5. Thus the actuation of the handle 13 will cause the actuator 64 to swing so that the latter is effective in engaging the coin projecting from the receptacle, thus swinging the supporting member 60 together with the retainer 85 about the shaft 14. In the same way, the presence of a coin in the path of finger 151^a will cause the receptacle to swing when shaft 14 is turned.

A trip element 110 preferably is pivotally supported above apron 53 and below the frame 17, having a rearwardly directed arm 113 that is engageable with an extension 133 of the member 130. As an article moves downwardly from the ends of supports 20, it engages the front portion of member 110, swinging the rear part 113 thereof upwardly into engagement with the extension 133 of member 130 and moving the latter about its pivot so that the member 85 is released from its position substantially in the plane of the plate 100. As the plate 60 reaches a position at a considerable angle to the vertical, the pressure of the actuator upon the project-

ing coin portion and the weight of the released member 85 is effective in swinging the latter into a substantially vertical plane so that the coins are moved out of engagement with the inclined edge 100, dropping from the coin receptacle as illustrated particularly in Fig. 2.

An extension 132 of member 130, disposed substantially at right angles to its plane of movement, is arranged to engage the end of the outwardly swinging retainer when the latter is released due to the movement of the locking member, and thus prevents the movement of the locking member into engagement with the other side of the swung retainer.

A suitable coin box 120 is disposed below the plate 60 as viewed in Figs. 2 and 6 at the left of the same, to receive the coins that are thus to be retained by the machine. As soon as handle 13 is released, actuator 64 returns to its normal retracted position under the action of spring 160, the projection 61 engaging plate 60. A stop member 141 mounted on frame 17 engages plate 60 to limit its movement in this direction (Fig. 6). A rearwardly directed projection 140 upon the portion 75 of the actuator engages the adjoining edge of member 85, thus being effective in swinging the latter about shaft 80 so that it is brought back into substantial alignment with plate 60, as the latter is substantially returned to its vertical position.

Due to its inertia retainer 85 normally swings somewhat beyond its normal position in the general plane of plate 60 as the latter engages stop 141 at the end of the return movement of the actuator under the influence of spring 160. Accordingly the sides 102 of the coin receptacle move any coins which have not been released out of engagement with the inclined edge 100 and permit them to drop to the right of plate 60, as viewed in Fig. 2. Coins may thus fall out of the receptacle and pass to the coin return chute 132. Obviously after the member 85 has swung to the right in this manner under the action of the spring 160, it will be returned by gravity to its normal position in the general plane of plate 60. The coin chute is provided with a continuation adjoining the return portion 19 that forms a substantially vertically disposed channel. A downwardly inclined element 136 is urged yieldably outward normally to prevent a coin passing downwardly through the open bottom of the channel. The opening 19 in the channel is opposite the element 136 and permits access from the exterior of the machine, so that the pressure of the finger upon a coin in this open portion of the channel will force the yieldably held coin against the element 136, so that the coin may pass the same and be removed from the open bottom of the channel.

If the wrong number of coins is deposited, for example but a single coin, when the machine is adjusted to act in response to two coins, the finger 151 of actuator 64 will move 5 past the end of the coin receptacle without engaging a coin to swing the same, and upon its return movement the actuator will be effective in swinging the lower part of member 85 away from the inclined edge 100 of plate 60 to release the coin to the return chute 132. The actuator performs this function due not only to the engagement of its projection 140 with retainer 85, but also due to the engagement 10 of lug 61 with the lower part of plate 60 which is effective in jarring the plate 60 so that the inertia of the weighted retainer 85 causes it to swing away from the locking element 130 and to release a coin or coins to the right of the supporting plate 60.

20 If a larger number of coins is deposited than is necessary to operate the machine, the movement of the actuator, including the part 75 thereof which forms the bottom of coin passage 70, will release coins from the latter, the pivoted plate 71 cooperating to permit this result.

From the foregoing it is evident that when the stop 91 is positioned to permit the machine to be operated in response to the desired 30 number and denomination of coins and that when that number and denomination of coins are inserted through slot 16, they pass through passage 70 to the swinging coin receiving receptacle where their faces are engaged by the opposite walls of member 85 and where their edges rest upon the inclined edge 100 of plate 60. The handle 13 is then rotated to move the shaft 14 and actuator 64 against the action of spring 160. The finger 40 151 of the actuator engages a projecting portion of the coin that was last received by the receptacle and causes the movement of the latter, including plate 60 and member 85. These parts move as a unit, since the locking 45 member 130 holds the lower part of member 85 substantially in alignment with plate 60 until the trip member 110 is actuated by the movement of an article downwardly through the delivery passage 55. It is evident that 50 this article is separated from the remainder of the group supported by members 20 due to the movement of the ejector elements 31 which are actuated by cranks 51 and link 50 in response to the swinging of the coin receptacle. As soon as the trip member is swung 55 downwardly to permit the passage of the article to the delivery opening 11, its rear portion is effective in swinging member 130 out of engagement with retainer 85 so that 60 the pressure of the actuator upon the projecting coin and/or gravity acting upon the retainer swings the latter out of alignment with the inclined plate 60, this position of the parts being shown in Figure 2, so that the coins 65 move out of engagement with the inclined

edge of the plate 60 and may thus drop to coin box 120. As soon as handle 13 is released, spring 160 is effective in returning actuator 64 to its normal position, which is determined by the engagement of the projection 61 thereof with support 60, and the fixed stop 141 engaging the latter. As the actuator is thus returned to its normal position, the projection 140 upon the same engages the front of member 85 to swing the latter back into alignment with the plate 60. Due to its inertia as well as its contact with projection 140, the retainer 85 moves past this position as the plate 60 engages the stop 141 upon reaching its vertical position; thus retainer 85 moves any coins which have not already been released to the box 120 to the other side of plate 60, thus permitting them to fall to the coin return chute 132.

If less than the required number of coins 85 is received by the swinging coin receptacle, the movement of the handle 13 and the consequent swinging of actuator 64 will not result in the movement of the coin receptacle or the delivery of an article by the dispensing 90 mechanism, but return movement of the actuator under the influence of spring 160 will cause its projections 61 and 140 to engage the parts of the coin receptacle in such a manner that the retainer 85 will swing about its pivotal support to release the deposited coin or coins to the return chute. Thus the projection 61 upon the actuator engages the lower part of the member 60, tending to throw its upper part in the opposite direction against the somewhat yieldable sheet metal stop 141, and the inertia of the weighted retainer will result in sufficient movement of its open lower end to move the edge of the coin out of engagement with the inclined supporting surface 100. The projection 140 upon the upper part of the actuator also will normally engage a part of the retainer 85 below its pivotal support, thus hitting the latter with sufficient force to tend to swing its open lower end away from edge 100. The retainer 85 will return to its proper inoperative position, however, due to the effect of the weighted extension 103, the side of the retainer then being held against the locking member 130.

It is evident that the return movement of the plate 60 is effective through the link 50 and crank 51 in swinging the ejector elements 31 back to their normal position, where they engage the foremost remaining member of the group of articles supported upon inclined members 20. The coin return portion of the machine is arranged so that a returned coin is held in a position where it may readily be engaged by the finger of a person in order to permit its removal from the machine, while the provision of a return receptacle that is exposed to the elements and which might collect a quantity of moisture, dust, or the like, is avoided.

If for any reason too many coins should be deposited or one of the same should be caught in the coin passage 70, the movement of the actuator will cause the bottom of this passage formed by plate 75 to be moved in relation to the remainder thereof to permit such a coin to drop out of the passage. Obviously the detector 170 is effective in preventing the operation of the machine by washers, although not interfering with the proper coin actuation.

It is evident that the positioning of the member 85 upon the inclined shaft 80 permits the ready removal of this member should the same be necessary and that the adjustment or removal of the stop 91 also may readily be effected.

From the foregoing, it is evident that I have provided a coin controlled machine which is adapted readily to be actuated in response to the movement of an exterior handle after the proper coin or number of coins has been deposited, and if there is an article contained within the machine to be delivered; if the supply of vendable articles is exhausted, or if the machine does not operate to deliver one of the same, the coin is returned to the operator of the machine. Furthermore, if but a single coin is deposited and the machine is adjusted for a plurality of coins, the deposited coin is automatically returned upon actuation of the operating handle 13. Furthermore, the machine is arranged so that it is not operable in response to washers or the like deposited as substitutes for coins, or in response to coins of improper denomination, and is arranged so that it may be substantially immune to injury due to exterior tampering, the depositing of foreign objects in the coin inlet passage or the like.

I claim:

1. A machine of the class described comprising articles delivery mechanism a swinging coin receptacle, said receptacle being arranged to hold a coin with a portion thereof projecting beyond its end, a swinging actuator engageable with the projecting coin portion to swing the receptacle, a bottom member and a retaining member cooperating to form said coin receptacle, said bottom member swinging about a fixed pivot and being operatively connected to the article delivery mechanism, said retaining member being pivoted to swing in relation to the bottom member, means normally locking the retaining member in a position in relation to the bottom member which results in the retention of the coin, trip mechanism effective to release said locking means when actuated by an article being delivered due to movement of the bottom member about its pivot, said retaining member being movable in response to the pressure imposed by the actuator upon the projecting coin portion to release the retained

coin when the trip mechanism has thus been actuated.

2. A machine of the class described comprising article delivery mechanism, a swinging actuator, a movable coin receptacle adapted to hold a portion of a coin in the path of the actuator, said receptacle being operatively connected to the article delivery mechanism, a retaining member forming a portion of the receptacle and movable to either side of the adjoining portion of the receptacle to release a coin at either one of two sides of that portion of the receptacle, locking means normally preventing the movement of the retainer to one side of said receptacle toward which it is urged by the pressure of the actuator upon the coin, trip mechanism operable by an article being delivered to release said locking means and the retainer, thereupon releasing the coin from the receptacle, said retaining member being movable in the other direction to release a coin at the opposite side if the article has not been delivered.

3. A machine of the class described comprising article delivery mechanism a swinging actuator, a coin receptacle to hold a portion of a coin in the path of the actuator, a support member pivotally mounted to swing about a fixed axis and forming the bottom of said receptacle, said support member being operatively connected to article deliver mechanism a retainer member pivotally mounted upon said support member, said retainer having parallel portions adapted to engage the faces of the coin and to cooperate with the member in forming the coin receptacle, a coin passage to direct a coin to the receptacle when the latter is in a substantially upright position, locking means normally holding the retainer against pivotal movement in relation to the support member, and means actuatable in response to an article being delivered by said delivery mechanism to release the locking means, the pressure of the actuator upon a coin projecting from the receptacle thereupon being effective in swinging the retainer in relation to the support member to move the coin out of engagement with the latter whereby it is released from the receptacle.

4. A machine of the class described, comprising a coin passage, a swinging member disposed adjoining the end of the passage, a coin retainer pivotally mounted upon the swing member, the latter having a portion to form the bottom of a receptacle receiving coins from the passage, an actuator movable between the passage and the receptacle and adapted to engage a coin projecting from the latter, article delivery mechanism operatively connected to the receptacle, means normally locking the retainer against pivotal movement in relation to the swinging member, trip mechanism to release said locking means in response to an article being delivered, said actuator engaging a coin projecting from the

receptacle and swinging the latter to actuate the delivery mechanism, the release of the locking means when the receptacle is thus swung by the actuator being effective in permitting the retainer to be swung in relation to the swinging member in response to the pressure of the actuator upon the projecting coin portion and thus to cause the coin to be released by the retainer.

5 5. A machine of the class described comprising article delivery mechanism a coin passage, a coin receptacle comprising a swinging support, said support providing the bottom for the receptacle, a pivot element on the support, a retainer depending from said element and providing a side for the receptacle, a locking member mounted upon the support and connected thereto by a pivotal element with its axis substantially at right angles to the axis about which the support swings, said locking member normally having a portion in engagement with the retainer, a trip mechanism actuatable in response to an article being delivered to move the locking member out of engagement with the retainer, a manually operable actuator movable into engagement with a coin carried by the coin receptacle and pressing the same against the retainer to swing the receptacle, the release 20 of said locking means permitting the pressure of the actuator upon the coin to cause the retainer to be swung in relation to the supporting member to release the coin.

25 6. A machine of the class described, comprising a coin passage, a swinging coin receptacle, article delivery mechanism operable by the movement of said receptacle said receptacle including a pivotally mounted supporting member providing an inclined bottom edge for the receptacle, a retaining plate pivotally mounted on the supporting member, a locking member pivotally mounted on the supporting member and having a portion normally engageable with the retaining plate, a trip mechanism operable in response to an article being delivered by said mechanism and provided with an element movable into engagement with the locking member to release the same from its engagement with the 30 plate, a swinging actuator engageable with a coin projecting from the coin receptacle and adapted to press the same against the retaining plate, the pressure of said actuator upon the coin being effective in causing the retaining plate to swing in relation to the supporting member when the locking member is released, thereby causing the coin to be moved out of engagement with the bottom of the receptacle so that it may drop from the same.

35 7. A machine of the class described, comprising a coin passage, a coin receptacle arranged to receive a coin from said passage, article delivery mechanism operable by the movement of said receptacle an actuator movable between said passage and receptacle

and engageable with a portion of a coin projecting from the latter, said receptacle including a supporting member swinging about a fixed axis and providing the bottom for the receptacle, and a retainer pivotally mounted upon the supporting member above the bottom of the receptacle and having parallel side portions forming the sides of the receptacle, locking means normally holding the retainer against pivotal movement in one direction in relation to the supporting member, the pressure of the actuator upon the projecting coin portion tending to force the retainer against this locking means, and thus being effective in swinging the receptacle until the locking means is released, and trip mechanism operable by an article being delivered to release the locking means to permit the retaining member to swing away from its normal position in relation to the supporting member whereby the coin within the receptacle is moved out of engagement with the bottom of the same and is released therefrom.

40 8. A machine of the class described comprising a coin passage, a coin receptacle aligned with the passage, article delivery mechanism operable by the movement of said receptacle said receptacle including a swinging support, said support including a portion providing an inclined supporting edge of substantially the thickness of a coin to engage the edge of a coin and thus to form the bottom of the receptacle, a pivot element carried by the supporting member above said inclined edge, a retainer having an upper portion engageable with the pivot member and having parallel side portions spaced at a distance greater than the thickness of a coin and forming the sides of the coin receptacle, an actuator movable between the coin passage and coin receptacle and engageable with a portion of a coin projecting from the latter, locking means carried upon the receptacle and normally tending to prevent the movement of the retainer and the supporting member when pressure is applied to the projecting coin portion by the actuator, trip mechanism operable by an article being delivered effective to release the locking member and to permit the retaining member to be moved due to the pressure upon the projecting coin portion so that the edge of the coin is no longer in engagement with the bottom of the receptacle but is released from the same, one side of the retainer having openings disposed above the bottom of the receptacle and a spring clip straddling the retainer, said clip having a finger engageable with any selected one of the openings in the retainer, whereby it forms the inner end of the coin receptacle, the openings in the retainer permitting the adjustment of the capacity of the receptacle to allow the same to accommodate coins of different numbers or denominations.

9. A machine of the class described comprising a coin passage, a coin receptacle arranged to receive a coin from said passage, article delivery mechanism operable by the movement of said receptacle an actuator movable between said passage and receptacle and engageable with a portion of a coin projecting from the latter, said receptacle including a support member, a fixed pivot element about which the support member swings, the latter providing the bottom for the coin receptacle, a pivot element carried by a portion of the support member above the part of the same which provides the bottom of the receptacle, a retaining member mounted on said last-named pivot element and having parallel side portions forming the sides of the coin receptacle, locking means normally holding the retainer against pivotal movement in one direction in relation to the support member, the pressure of the actuator upon the projecting coin portion tending to force the retainer against this locking means and thus being effective in swinging the receptacle until said means is released, trip mechanism operable by an article being delivered to release the locking means to permit the retaining member to swing away from its normal position under the pressure of the actuator upon the coin in order to release the latter, a spring normally tending to return the actuator to its inoperative position, a part of the actuator being engageable with the supporting member to return the latter to its inoperative position, stops to limit the return movement of the actuator and supporting member, the inertia of the retainer causing it to swing away from the supporting member to release a coin at the side of that member remote from the locking means when the supporting member is thus returned to its normal inoperative position under the action of the spring.
10. A machine of the class described comprising a coin passage, a coin receptacle arranged to receive a coin from said passage, article delivery mechanism operable by the movement of said receptacle, an actuator movable between said passage and receptacle and engageable with a portion of a coin projecting from the latter, said receptacle including a supporting member, a fixed pivot element about which the supporting member swings, the latter providing the bottom for the coin receptacle, a pivot element carried by a portion of the supporting member above the part of the same which provides the bottom of the receptacle, a retaining member depending from said last-named pivot element and having parallel side portions forming the sides of the coin receptacle, locking means normally holding the retainer against pivotal movement in one direction in relation to the supporting member, the pressure of the actuator upon the projecting coin portion tending to force the retainer against this locking

means and thus being effective in swinging the receptacle until said means is released, trip mechanism operable by an article being delivered to release the locking means to permit the retaining member to swing to release the coin, a spring normally tending to return the supporting member to its inoperative position, a part of the latter being engageable with the supporting member to return said member to its inoperative position, and a stop to limit the return movement of the supporting member, the retainer forming a weighted portion swinging about its pivot element and having sufficient inertia to swing into a coin releasing position when the supporting member is thus returned to its normal position under the action of the spring.

11. A machine of the class described comprising article delivery mechanism a coin passage, a coin receptacle arranged to receive a coin from said passage, article delivery mechanism operable by the movement of said receptacle, an actuator movable between said passage and receptacle and engageable with a portion of a coin projecting from the latter, said receptacle including a supporting member and a retainer, a fixed pivot element about which the supporting member swings, means operatively connecting the supporting member and said mechanism the latter providing the bottom for the coin receptacle, a pivot element carried by a portion of the supporting member above the bottom of the receptacle, said retainer comprising parallel plate portions to form the sides of the coin receptacle and being swingable in either direction, means normally preventing the movement of the retainer in one direction and permitting its movement in that direction in response to an article being delivered by the delivery mechanism, whereby coins dropping in this direction may be retained, and means effective to swing the retainer in the opposite direction to release coins and a return chute to receive the coins thus released.

12. A machine of the class described comprising a coin passage, a coin receptacle arranged to receive a coin from said passage, an actuator movable between said passage and receptacle and engageable with a portion of a coin projecting from the latter, said receptacle including a supporting member and a retainer, a fixed pivot element about which the supporting member swings, the latter providing the bottom for the coin receptacle, article delivery mechanism operable by the swinging of said supporting member, a pivot element carried by a portion of the supporting member above the bottom of the receptacle, said retainer having parallel side portions to form the sides of the coin receptacle and depending from the last-named pivot element to provide a weighted member swinging from the same, locking means normally preventing

the swinging of the retainer in one direction in relation to the supporting member, the pressure of the actuator upon a projecting coin portion being effective in holding the retainer against the locking means and in causing the retainer to swing in the direction of the locking means to release a coin when the locking means is moved out of engagement with the retainer, spring means normally tending to return the supporting member to its inoperative position, a stop defining said position, means for releasing the locking means in response to an article being delivered, the inertia of the weighted retainer member being sufficient to cause it to swing away from the bottom of the receptacle when the supporting member is thus returned to its normal inoperative position under the action of the spring, whereby a coin not released by the movement of the locking means may be released at the other side of the supporting member and a return chute to receive a coin thus released.

13. A machine of the class described comprising a coin passage, a coin receptacle arranged to receive a coin from said passage, article delivery mechanism connected to said receptacle an actuator movable between said passage and receptacle and engageable with a portion of a coin projecting from the latter, said receptacle including a supporting member, a fixed pivot about which the supporting member swings, the latter providing the bottom for the coin receptacle, a pivot element carried by a portion of the supporting member above the bottom of the receptacle and a retainer, said retainer being pivotally mounted upon said element and depending therefrom, locking means normally preventing the retainer from moving in relation to the receptacle when the actuator engages a projecting coin, trip means actuatable by an article being delivered to release said locking means, a spring normally tending to move the actuator to inoperative position, a part of the actuator being engageable with the supporting member as the former approaches its inoperative position, a stop to define the inoperative position of supporting member, the actuator being effective when thus returning to its inoperative position in causing the movement of the retainer away from the supporting member to release a coin from the receptacle, whereby a coin may be released that does not project from the receptacle into the path of the actuator.

14. A machine of the class described comprising a coin passage, a swinging coin receptacle, article delivery mechanism actuatable thereby, a retainer pivotally mounted upon the receptacle, an actuator movable between the passage and receptacle and engageable with a coin projecting from the latter, said retainer forming the sides of the coin receptacle and including parallel side walls, one at

least of said walls having a plurality of spaced openings, and a stop selectively engageable with any of said openings and adapted when in operative position to span the space between the walls of the retainer and thus form the end of the coin passage, and means for releasing a coin from the receptacle, said means being actuatable by an article being delivered.

15. A machine of the class described comprising a coin operated mechanism, means associated therewith to permit the retention of a coin in response to the delivery of an article by the machine, and means associated therewith to return a deposited coin when an article is not thus delivered, a coin passage to receive a coin to be returned, said passage including a channel having cross-sectional dimension of the order of that of a coin, and a member yieldably urging a coin against the opposite wall of the channel, an opening in said opposite wall of the channel through which the finger may extend to apply pressure to the coin and to cause the member to release the same from frictional engagement with the opposite wall of the passage, said channel being an open end through which the coin may then be removed.

16. A machine of the class described comprising a swinging actuator, article delivery mechanism connected thereto, a coin receptacle adapted to hold a portion of a coin in the path of the actuator, said receptacle including a bottom member pivotally mounted to swing about a fixed axis, a retainer pivotally connected to the bottom member and providing spaced depending portions, an abutment upon one side of the bottom member, the material of the retainer being so distributed that gravity normally holds it against the abutment, the pressure of the actuator upon a projecting coin portion being normally effective in pressing the retainer against the abutment, a spring tending to return the actuator to inoperative position, said actuator then being effective in causing the retainer to swing in relation to the bottom member to release a coin from the receptacle.

17. A machine of the class described comprising a swinging actuator, article delivery mechanism connected thereto, a coin receptacle adapted to hold a portion of a coin in the path of the actuator, said receptacle including a bottom member pivotally mounted to swing about a fixed axis, a retainer pivotally connected to the bottom member and providing spaced depending portions, an abutment upon one side of the bottom member, the pressure of the actuator upon a projecting coin portion normally being effective in pressing the retainer against the abutment, a spring tending to return the actuator to inoperative position, a stop, said actuator having a part engaging the bottom member and

pressing another part of the same against the stop, the return movement of the actuator causing it to jar the bottom member into firm engagement with its stop so that the retainer swings away from the abutment to release a coin upon the other side of said member.

18. A machine of the class described comprising a coin passage, a coin receptacle arranged to receive a coin from said passage, article-delivery mechanism operable by the movement of said receptacle, an actuator movable between said passage and receptacle and adapted to engage a portion of a coin projecting from the latter, said receptacle including a supporting member swinging about a fixed axis and providing the bottom for the receptacle and a retainer mounted upon the supporting member, said retainer being pivotally connected to a portion of the supporting member above the bottom of the receptacle and having parallel side portions forming the sides of the receptacle, locking means normally holding the retainer against pivotal movement in one direction in relation to the supporting member, the pressure of the actuator upon the projecting coin portion tending to force the retainer in this direction and thus being effective in swinging the receptacle until the locking means is released, trip mechanism operable by an article being delivered to release the locking means to permit the retaining member to swing away from its normal position in relation to the supporting member whereby the coin within the receptacle is moved out of engagement with the bottom of the same and released therefrom, stop elements limiting the movement of the actuator, a spring tending to oppose the movement of the actuator into engagement with the coin portion, and a projection carried by the actuator and engageable with the side of the same toward which the actuator is moved when it engages a coin, said projection engaging a portion of the retaining member which is below its pivotal connection with the supporting plate, whereby when the actuator returns to its inactive position under the influence of the spring the projection is effective in causing the retainer to swing in relation to the receptacle, and means associated with the retainer for adjusting the capacity of the receptacle to permit the same to accommodate coins of different numbers or denominations.
19. A machine of the class described comprising a coin passage, article-delivery mechanism operable by the movement of said receptacle, a coin receptacle aligned with the passage, said receptacle including a swinging support, said support including a portion of substantially the thickness of a coin with an inclined supporting edge to engage the edge of a coin and thus to form the bottom of the receptacle, an inclined pivot member carried by the supporting member, a re-

tainier having an upper portion engageable with the pivot member and having parallel side portion spaced at a distance greater than the thickness of a coin and thus forming the sides of the coin receptacle, an actuator movable between the coin passage and coin receptacle and engageable with a portion of a coin projecting from the latter, locking means carried upon the receptacle and normally tending to prevent the movement of the retainer in relation to the supporting member when pressure is applied to the projecting coin portion by the actuator, and trip mechanism operable by an article being delivered effective to release the locking member and to permit the retaining member to be moved due to the pressure upon the projecting coin portion so that the edge of the coin is no longer in engagement with the bottom of the receptacle but is released from the same, a spring tending to return the actuator to its normal inoperative position, a stop defining this position, a projection upon the actuator engaging the side of the retaining member below its portion that is mounted upon the pivotal support whereby the spring is effective in causing relative movement of the retainer in relation to the supporting member to release the coin if the same has not already been released in response to the actuation of the trip mechanism.

20. Apparatus of the class described comprising dispensing means, a swinging receptacle for supporting coins of any of a plurality of selected denominations in actuating position, actuating means engageable with any coin occupying such an actuating position and thereby to swing the receptacle and initiate operation of the dispensing means and means actuated by an article being delivered to release coins from said receptacle.

21. Apparatus of the class described comprising dispensing means, a swinging coin receptacle having side walls spaced to receive coins between them, said side walls having openings arranged to expose a portion of a coin occupying a definite position within the receptacle, a movable actuator adapted to move through said opening into engagement with the exposed portion of the coin and by continued movement thereafter to swing the receptacle and initiate actuation of the dispensing means and means actuated by an article being delivered to release coins from said receptacle.

22. Apparatus of the class described comprising dispensing means, a swinging coin receptacle adapted to hold a single coin or a row of coins collectively having the same monetary value as said single coin, said receptacle being so arranged as to expose a definite portion of said single coin or the endmost only of the row of coins, movable

actuator means adapted to engage the exposed portion of any such coin and by contact with the coin to swing the receptacle and initiate operation of the dispensing means, and means actuated by an article being delivered to release coins from said receptacle.

23. Apparatus of the class described comprising dispensing means, a swinging coin receptacle, and actuating means, said actuating means comprising movable parts adapted respectively to engage a single coin within the receptacle or the endmost of a row of coins in the receptacle collectively equalling the monetary value of said single coin, and by engagement with a coin to swing the receptacle and initiate movement of the dispensing means, and means actuated by an article being delivered to release coins from said receptacle.

24. Apparatus of the class described comprising dispensing means, a swinging coin receptacle provided with stop means for limiting the movement of the coins of different denominations, respectively, actuating means cooperating with coins detained by the operation of any such stop means and thereby to swing the receptacle and initiate operation of the dispensing means and means actuated by an article being delivered to release coins from said receptacle.

25. Apparatus of the class described comprising dispensing means, a swinging coin receptacle having a bottom and spaced side walls, one at least of said walls having openings therethrough at predetermined points, and stop means selectively positionable in any of said openings for limiting the number or denomination of coins which may be placed within the receptacle, an actuator engageable with coins which are positioned by said stop means and thus swinging the receptacle, the swinging movement of the receptacle operating the dispensing means, and means operable by an article being delivered to release coins from said receptacle.

26. Apparatus of the class described comprising dispensing means, an elongate coin receptacle having spaced side walls, one at least of said walls having a plurality of openings therethrough, and a spring clip adjustable longitudinally of the receptacle and comprising a stop finger adapted to be positioned in any selected one of said openings, an actuator engageable with coins which are positioned by said finger and thus swinging the receptacle, the swinging movement of the receptacle operating the dispensing means, and means operable by an article being delivered to release coins from said receptacle.

27. Apparatus of the class described comprising dispensing means, a swinging receptacle having a bottom adapted to support a coin or coins, and side walls spaced to receive coins between them, adjustable stop means for determining the position respectively of

a single coin of large denomination or of a row of coins of smaller denomination collectively equalling the monetary value of the single coin, the side walls of the chute being so designed as to expose a portion of such single coin or of the endmost coin of the row of coins, a rotary actuator shaft, and fingers carried by the shaft adapted respectively to engage the exposed portion of the single coin or the endmost only of the row of coins, and by such engagement to initiate operation of the dispensing means and means actuated by an article being delivered to release coins from said receptacle.

28. Apparatus of the class described comprising dispensing means, a swinging coin receptacle and means associated therewith for initiating operation of the dispensing means when the receptacle is swung from its normal position, said receptacle having stop means for determining the position within the receptacle of a greater or lesser number of coins respectively having the same aggregate monetary value, the receptacle being so constructed and arranged as to expose a predetermined portion of the endmost coin only of such greater or lesser number, respectively, and movable actuating means engageable with such exposed coin and thereby swinging the receptacle from its normal position and means operable in response to an article being delivered to release coins from said receptacle.

29. Apparatus of the class described comprising dispensing means, a swinging coin receptacle having bottom and side walls spaced to receive coins between them, spaced stop devices adapted respectively to determine the position of coins of different denominations within the receptacle, one of such stops being so disposed that a coin of predetermined denomination will project beyond the end of a receptacle, the side walls of a receptacle having openings to expose a coin positioned by another of said stops, and a rotary actuator shaft and fingers carried by the shaft adapted respectively to engage exposed portions of coins positioned by the respective stops and by such engagement to swing the receptacle and thereby to initiate operation of the dispensing means and means actuated by an article being delivered to release coins from said receptacle.

30. A machine of the class described comprising a swinging coin receptacle being arranged to hold a coin with a portion thereof projecting beyond the end of the receptacle, a swinging actuator adapted to engage such projecting coin to swing the receptacle, said receptacle including a swinging support having a portion to form the bottom of the receptacle and a retaining member pivotally mounted upon the support, said retaining member comprising substantially parallel side portions that cooperate with the afore-

said portion of the supporting member in forming the coin receptacle, delivery mechanism actuatable in response to the tipping of the supporting member about its pivot, and locking means normally holding the retaining member in fixed relation to the support, said means being releasable by an article being delivered to permit the swinging of the retaining member under the action of gravity to one side of its normal position in relation to the tipped supporting member to release coins to a suitable coin retaining part of the machine.

31. A machine of the class described comprising a coin passage, a coin receptacle arranged to receive a coin from said passage, an actuator movable between said passage and receptacle and engageable with a portion of a coin projecting from the latter, said receptacle including a supporting member, a fixed pivot element about which the supporting member swings, the latter providing the bottom for the coin receptacle, a pivot element carried by a portion of the supporting member above the part of the same which provides the bottom of the receptacle, a retainer depending from said last-named pivot element and forming a side of the coin receptacle, delivery mechanism actuatable by the swinging of the supporting member about the first-named pivot element in response to the pressure of the actuator upon a projecting coin portion, means operable in response to an article being delivered to release a coin from the receptacle, said retainer being movable in relation to the supporting member to release coins from the receptacle when the delivery mechanism has not been actuated, a spring tending to return the actuator to its inoperative position, a part of the actuator being engageable with the supporting member to effect the concomitant return of the latter to the inoperative position, a stop defining said position, the retainer being so arranged that its inertia upon thus returning toward its normal inoperative position under the action of actuator spring will cause it to swing away from the supporting member to release a coin not previously released from the receptacle.

Signed by me at Boston, Massachusetts,
this 2nd day of October, 1929.

ERNEST C. WHITING.
